UNITED STATES PATENT OFFICE

PAUL MACHOWICZ, OF JAMAICA, NEW YORK

DESIGN FOR A LAMP CASING

Application filed June 7, 1930. Serial No. 35,972. Term of patent 7 years.

To all whom it may concern:

Be it known that I, PAUL MACHOWICZ, a citizen of Poland, and a resident of the city of New York (Jamaica, borough of Queens), in the county of Queens and State of New York, have invented the new, original, and ornamental Design for Lamp Casings, of which the following is a specification.

Reference being had to the accompanying drawing, forming a part thereof:

I claim:

The ornamental design for a lamp casing, substantially as shown.

PAUL MACHOWICZ.
